UNITED STATES PATENT OFFICE

THEODOR KOCH, SR., OF BUREN, SWITZERLAND, ASSIGNOR TO M. LOUIS GRAY, OF NEW YORK, N. Y.

TIMEPIECE

Application filed February 18, 1928, Serial No. 255,463, and in Switzerland March 18, 1927.

This invention relates to timepieces, particularly watches, such as wrist-watches, and has for its main object to provide an improved construction of balance-cock for the 5 clockwork thereof.

According to the invention there is provided a clockwork movement, particularly for watches, characterized in that the head of the balance-cock has two lugs, whereof 10 one carries, as usual, the small block for the balance spring, while the other serves for receiving at least one part of the devices mounted on the balance-cock.

Two embodiments of the invention are illustrated diagrammatically by way of example in the accompanying drawing, wherein:

Figure 1 is a plan showing one form of balance-cock according to the invention, and 20 Figure 2 is a section taken on the line II—II in Figure 1;

Figure 3 is a plan showing the second form of balance-cock.

Like reference characters designate like 25 parts in all the views.

Referring to the drawing, the head of a balance-cock 1 has two symmetrically arranged lugs 2, 3 whereof the lug 2 carries, as usual, the small block 4 for attaching one 30 end of the balance spring, while the lug 3, in the construction shown in Figures 1 and 2, has a shock-absorbing spring 5 secured on 1 by means of a screw 6. This spring 5 serves, in a manner known in itself, for taking up axial pressures of the balance arbor 35 due to shaking or blows. It may be stated that this purpose is not novel, as such shock-absorbing springs or equivalent means have been proposed heretofore, but the herein-described and illustrated arrangement and construction of the shock-absorbing spring 5 is novel. In consequence of this arrangement 40 not only does this spring function better, but an improved distribution of all the members mounted on the balance-cock results. As shown in the drawing the spring 5 is relatively large; it has an arm that is screwed down on the lug 3 and bears resiliently on an annular portion on the cover stone 7. The latter lies freely on the balance-cock, in a cir-

cular hole of a regulator plate 8. The bearing stone 10 slidably mounted in the balance-cock is provided with a central perforation 10a for pivotally receiving the one end of the balance arbor (not shown). The regulator plate 8 is attached by means of two screws 11 on the balance-cock. The regulator 55 12 is rotatably mounted on the plate 8 in known manner by means of a dovetail joint. The regulator pointer 12' as well as the short-tail-piece 12'' and the regulator pins lie in the axis of symmetry of the balance-cock, at right-angles to the lugs of the latter.

On the regulator plate 8 a set-screw 13 is 60 provided whose stem extends through a hole in the spring 5 so that the deflection of the latter is limited by the head of the screw, and can be adjusted accordingly.

Obviously, movement of the arbor in the 65 direction of the bearing stone 10 will move the latter against the abutment stone 7 which will in turn press against the spring 5, said spring consequently absorbing the shock.

The modification shown in Figure 3 is similar in general to the form shown in Figs. 1 and 2 but differs therefrom in that, in Figure 3, the indicator 12' has been placed above the lug 3, while the arm of the spring 5 is arranged at the place generally occupied by the indicator, i. e. on the back of the balance-cock. In this case, the indicator must, of course, be shorter which, however, is of no importance. On the other hand, the arm of 70 the spring 5 may be much longer as there is much more room available on the back of the balance-cock than on the lug 3. Consequently, in this arrangement a better and more durable shock-absorbing spring 5 can be used 75 than in the construction according to Figures 1 and 2.

The invention can be applied not only to pocket and wrist watches, but also to timepieces for automobiles and other vehicles and 80 in all clockwork movements comprising a balance-cock.

Various modifications may be made in the 85 details of construction described above without departing from the invention.

I claim:—

1. In a clockwork movement, the combination of a balance-cock having a head, a bearing member having a central perforation for receiving one end of the arbor, slidably mounted on said head, an abutment member movably mounted on said head in overlying relation to said bearing member, a shock absorbing member movable with respect to said abutment member and bearing against the latter, and means for adjustably limiting movement of said shock absorbing member.
2. In a clockwork movement, the combination of a balance-cock having a head, a bearing member adapted to receive one end of an arbor, mounted on said head, a shock absorbing member for said bearing member, and means for adjustably limiting movement of said shock absorbing member.
3. In a clockwork movement, the combination of a balance-cock having a head, a bearing member adapted to receive one end of an arbor, mounted on said head, an abutment member mounted in overlying relation to said bearing member, a shock absorbing member bearing against said abutment member, and means for adjustably limiting movement of said shock absorbing member.
4. In a clockwork movement, the combination of a balance-cock having a head, a bearing member for one end of an arbor, mounted on said head, a cover stone overlying said bearing member, a regulator plate fixed to said head and disposed about said cover stone, a regulator having an indicator retained on the said head by said regulator plate, a shock absorbing spring attached to said head and having a portion adapted to contact said cover stone, said spring having an opening, an adjusting screw slidably extending through said opening and screwed to said plate, said screw having a head adapted to contact the top of said spring for limiting upward movement thereof.
5. In testimony whereof I affix my signature.
THEODOR KOCH, Sr.
